UNITED STATES PATENT OFFICE.

WILLIAM M. DOUGLAS, OF GALVESTON, TEXAS.

PROJECTILE.

1,060,227.

Specification of Letters Patent. Patented Aug. 5, 1913.

Application filed August 16, 1912. Serial No. 715,404.

To all whom it may concern:

Be it known that I, WILLIAM M. DOUGLAS, a citizen of the United States, residing at Galveston, in the county of Galveston 5 and State of Texas, have invented certain new and useful Improvements in Projectiles, of which the following is a specification.

The present invention relates to projectiles and has particular reference to a shell which is adapted to be fired from a gun to penetrate the object aimed at and subsequently explode therein.

An important object of the invention is 15 to provide a projectile of the above mentioned character, so constructed that the same will have a high armor penetrating efficiency and a very large explosive material carrying capacity, whereby the explosion of the shell subsequently to its penetration into or through the armor will be very disastrous.

A further object of the invention is to provide a shell of the above mentioned character, which is accurate in flight through long ranges and capable of proper penetration and exploding in a disastrous manner far in excess of the present armor piercing shells and equaling the present torpedo 30 shells.

A further object of the invention is to provide a projectile of the above mentioned character, which is comparatively safe to handle, easy to manufacture, and 35 may be made in any desired caliber.

Other objects and advantages of the invention will be apparent during the course of the following description.

In the accompanying drawings forming 40 a part of this specification and in which like numerals are employed to designate like parts throughout the same, Figure 1 is a side view of my improved shell, Fig. 2 is a central longitudinal sectional view 45 through the same, Fig. 3 is a side view of the inner frame or body portion of the shell, Fig. 4 is a horizontal sectional view taken on line 4—4 of Fig. 2, Fig. 5 is a side view of the molded explosive, Fig. 6 is 50 a horizontal sectional view taken on line 6—6 of Fig. 5, Fig. 7 is a side view, partly in section, of a slightly different form of the invention, and, Fig. 8 is a horizontal sectional view taken on line 8—8 of Fig. 7.

55 In the drawings wherein for the purpose

of illustration, I have shown a preferred embodiment of my invention, the numeral 9 designates an inner frame or body portion of the projectile, which is formed of very hard steel. This inner frame comprises a 60 solid head 10, which is suitably tapered or of the proper contour to successfully penetrate armor plate. Formed integral with this penetrating head 10 are legs 11, which are spaced and preferably diametrically arranged, as clearly shown in Fig. 4. These legs are stiffened or reinforced by inner longitudinal ribs 12, as shown. The numeral 13 designates a preferably previously 65 molded mass of gun cotton or other explosive, adapted for insertion between the legs 11 and having longitudinal openings formed therein to receive the legs. The outer surface or periphery of the explosive mass or charge 13 is preferably flush with 70 the outer surface of the legs 11, as shown. 75

Attention is called to the distribution and amount of the metal in the frame 9, whereby the shell has a high armor plate penetrating efficiency and a very large chamber 80 or space is provided for holding the maximum amount of explosive charge. The numeral 14 designates a base, which is attached to reduced extensions 15 of the legs 11, by means of bolts or rivets 16. The base 85 14 is provided with an annular recess to receive a rotating ring 17, which is rigidly connected with the base 14 and serves to impart rotation to the shell. Surrounding the legs 11 is a jacket 18, formed of mild 90 steel and connected with the legs 11 at one end, by the bolts or rivets 16, as shown. Surrounding the penetrating head 10 is a cap or wind shield 19, which is suitably 95 tapered or of a contour to insure accuracy in flight of the shell. This cap 19 is preferably formed of mild steel and is connected with the jacket 18 by bolts or rivets 20, which preferably have connection with the legs 11. At its ends the cap 19 is provided with a screw-threaded opening, which is normally closed by a bolt-like plug 21.

Mounted upon the ends of the penetrating head 10 is a protecting block or cap 22, which is formed of soft steel and is held 105 from accidental displacement by fixed arms 23. The function of this protecting cap or block 22 is to absorb the energy or impact and thus relieve the inner frame of any considerable strain, while producing an elas- 110

tic dishing of the armor plate fired at. The function of the plug 21 is to provide an opening for the introduction of water, if required, to wet down the gun cotton or explosive mass 13.

Connected with the base 14 is a centrifugal fuse 24 of any well known or preferred type. The numeral 25 designates a detonator attached to the centrifugal fuse and 10 preferably formed of dry gun cotton.

In Figs. 7 and 8, I have dispensed with the jacket 18 and have substituted therefor panels 26, which are preferably formed of mild steel. These panels are of course 15 curved in cross-section to conform to the curvature of the legs. The panels 26 may be held in place by any suitable means. It is thus seen that the panels 26 together with the legs 11 form a large chamber for receiving the explosive mass. When the explosive mass or charge is of powder or the like and is fed into the chamber formed by the panels 26 and legs 11 by removing the base 14, said panels 26 may be connected 20 with reinforcing spiders 27. I may also dispense with these spiders and cast the panels 26 integral with the legs 11.

The operation of the projectile is as follows:—The projectile is shot from a gun 30 properly aimed at the object to be hit. The wind shield or cap 19 causes the projectile to have accuracy in flight. When the projectile strikes the armor plate or the like, the head 10 penetrates the same and the explosive mass 13 explodes soon afterward. The reinforcing legs 11 strengthen the inner 35 frame or body portion of the projectile and also provide a very large chamber or recess for holding the maximum amount of explosive charge, whereby the explosion which occurs after the penetration of the armor plate will be very disastrous.

I wish it understood that I do not restrict myself to the employment of gun cotton as 40 an explosive agent alone, as any well known or preferred type of explosive agent may be employed. It is ordinarily preferable, however, to employ an explosive agent which may be molded into a suitable form, to be 45 slipped into the space or opening formed within the legs 11.

It is to be understood that I do not restrict myself to the forms of my invention herewith set forth, but that certain changes 50 in the shapes, sizes, and arrangements of parts may be resorted to without departing from the spirit of the invention or the scope of the subjoined claims.

Having thus described my invention, I 55 claim:—

1. In a projectile of the character described, an inner frame including a penetrating head carrying trailing spaced legs for providing a very large chamber, an explosive charge disposed within the chamber,

and means to explode said explosive charge after the impact of the penetrating head with the armor plate or other object aimed at.

2. In a projectile of the character described, an inner frame including a penetrating head carrying a suitable number of spaced trailing legs to provide a very large chamber within and between the same, a mass of explosive material disposed within said chamber, means disposed adjacent the spaced legs to prevent the explosive material from passing between the same out of its chamber, and means to explode said mass of explosive material after the impact of the penetrating head with the armor plate or other object aimed at. 70 75

3. In a projectile of the character described, an inner frame comprising a penetrating head carrying spaced trailing legs 80 suitably stiffened by reinforcing ribs, a jacket surrounding the spaced legs to form therewith a large chamber, a mass of explosive material disposed within said large chamber, and means to explode said mass of explosive material after the penetrating head impacts with the armor plate or other object aimed at. 85 90

4. In a projectile of the character described, an inner frame comprising a penetrating head carrying spaced trailing legs 95 suitably stiffened by reinforcing ribs, a jacket surrounding the spaced legs to form therewith a large chamber, a mass of explosive material disposed within said large chamber, means to explode said mass of explosive material after the penetrating head impacts with the armor plate or other object aimed at, and a suitably tapered cap surrounding the penetrating head and connected therewith to insure accuracy in flight of the projectile. 100 105

5. In a projectile of the character described, an inner frame comprising a penetrating head carrying spaced trailing legs 110 providing therebetween a large chamber, a suitably molded mass of explosive material adapted for insertion within the chamber through the open end of the same, a base connected with said legs to close said open 115 end of the chamber, a suitably long tapered cap surrounding the penetrating head and connected therewith to insure accurate flight of the projectile, and means to explode said explosive material after the impact of the penetrating head with the armor plate or other object aimed at. 120

6. In a projectile of the character described, an inner frame comprising a suitably tapered penetrating head carrying 125 spaced substantially diametrically arranged longitudinal trailing legs reinforced with longitudinal ribs and providing a large chamber having one end thereof normally open, a jacket surrounding the legs, a mass 130

- of explosive material disposed within the chamber, a base connected with the legs to close the open end of the chamber, means associated with the base to explode the mass 5 of explosive material after the penetrating head impacts with the armor plate or other object aimed at, a suitably long and tapered cap surrounding the penetrating head and connected with the jacket to insure accuracy 10 in flight of the projectile, and a protecting cap formed of soft steel and mounted upon the end of the penetrating head between the same and the ends of the first named cap.
7. In a projectile of the character described, 15 a penetrating head, longitudinally extending suitably stiff trailing legs connected with the penetrating head and spaced relatively far apart for providing a maximum charge receiving chamber which extends for a considerable distance outwardly and radially beyond the inner surfaces of the 20
- trailing legs, and an explosive charge disposed within the chamber.
8. In a projectile of the character described, a penetrating head, longitudinally 25 extending suitably stiff trailing legs connected with the trailing end of the penetrating head and spaced relatively far apart for providing a maximum charge receiving chamber which extends for a considerable distance outwardly and radially beyond the inner surfaces of the trailing legs, an explosive charge disposed within the chamber, a base connected with the legs, and means carried by the base to explode the explosive charge. 30
- 35
- In testimony whereof I affix my signature in presence of two witnesses.
